UNITED STATES PATENT OFFICE.

CLARENCE E. SCOTT, OF NORRISTOWN, PENNSYLVANIA, ASSIGNOR TO YORK HEATING AND VENTILATING CORPORATION, OF PHILADELPHIA, PENNSYLVANIA, A CORPORATION OF PENNSYLVANIA.

FAN-HOUSING CONSTRUCTION.

Application filed May 17, 1927. Serial No. 192,086.

The present invention relates to fan structures and more particularly to a fan housing permitting removal of a fan assembly as a unit.

5 In fan housings and casings as heretofore constructed, repair and replacement of fans have been expensive and quite laborious, because such constructions have necessitated the removal of the fan shaft by drawing 10 it axially out of the fan and out of the fan housing. Often the unit in which the fan is mounted is so located with respect to room walls and other machines or equipment as to make it impossible, except with great 15 difficulty, to withdraw such shafts, and as a result the unit is obliged to be out of use for a considerable period while repairs are made.

20 Some of the objects of the present invention are to provide an improved construction for fan housings and casings; to provide means whereby a fan and its parts can be quickly and economically removed from its housing; to provide a structure whereby a 25 fan assembly can be lifted out of its housing as a complete unit, such removal taking place in a plane intersecting the axis of the fan shaft; to provide a fan housing having means for allowing the passage of a fan 30 shaft in combination with a closure structure for normally closing such means; and to provide other improvements as will hereinafter appear.

35 In the accompanying drawings, Fig. 1 represents a plan of a blower unit embodying one form of the present invention; Fig. 2 represents a section on line 2—2 of Fig. 1; Fig. 3 represents a section on line 3—3 of Fig. 2; Fig. 4 represents a section on line 40 4—4 of Fig. 2; Fig. 5 represents a plan detail of one of the removal top plates; and Fig. 6 represents a detail of the slot construction in the inlet case.

45 Referring to the drawings, one form of the present invention is shown as applied to a casing 10 for a plurality of fans 11 mounted upon a common driven shaft 12 which is suitably journaled upon the casing in any well known manner. The fans 11 are 50 respectively confined in volute housings 13, having truncated inlets 14 at opposite ends of each fan, these inlets being formed respectively in the side walls 15 of the housings. The top of each housing 13 is left

open to provide discharge outlets 16 for the 55 air or gas drawn through the casing 10 by the action of the fans 11. In the present embodiment of the invention, the casing 10 is that of a unit heater or heat diffusing means wherein air is drawn through the 60 casing 10 in contact with a heated coil and then discharged into a room for heating purposes.

For the purpose of gaining access to the fan shaft at all points in its length, the casing 10 is provided with a top plate 17 in the form of a strip running the length of the casing but of a width to leave plenty of space to allow the fans 11 to be removed without interference from this plate 17. As 70 here shown, the plate 17 is fastened along its outer edge to an angle 18 by bolts 19 and has its inner edge provided with support strips 20 which project between the respective fan housing walls and the end housing 75 walls and the end of the casing 10. Preferably these strips 20 are spot welded to the plate 17 as an inexpensive and effective way of anchoring them. Each of these strips 20 forms a support for one end of one of a 80 number of removable top sections 21, the other ends of which seat upon an angle iron 22 and are fastened by bolts 23. The top sections 21 respectively close the space between adjacent fan housing walls 15 and 85 the space between each end housing wall 15 and its juxtaposed casing wall.

In order to provide for the removal of the shaft 12 and its assembled fan structure as a unit, slots 24 are cut in aligned 90 axial relation in the housing walls 15 and open into like slots 25 cut in the truncated inlets 14. Preferably, the several slots 24 have an angular slant radially from the shaft 12, so that in removing the fan unit it 95 will be properly guided to the openings 16. These series of slots 24 and 25 allow the shaft 12 with the fan assembly to be lifted bodily upward and outward through the portion of the top which is not closed by the 100 plate 17.

For covering the slots 24 and 25, each of the top plates 21 is provided with attached closures 26 for covering the slots 24 in the vertical walls of each housing, and these 105 closures 26 are in turn formed with lateral cover member 27 for closing the slots 25. The closures 26 are arranged to have sliding

interfitting engagement with the housing walls, and to that end each has its side edges reversely turned as shown at 28 to receive the like formed edges 30 of the slots 25. 5 Thus each end removable top plate 21 will have one closure 26 and the intermediate removable top plates 21 will each have two closures 26. In consequence, when the top plates 21 are fixed to the casing 10, a complete unitary housing is provided for the fan assembly, and the only openings in the top are the necessary discharge outlets 16.

When it is desired to remove the fan assembly from the housings, it becomes a simple matter because upon taking out the fastening bolts 23, each top plate 21 can be lifted to carry with it the closures 26 and 27, since these latter will slide out of the interfitting guides and thereby open the slots 24 and 25 20 for the free passage of the shaft 12. This construction makes fan repair and replacement extremely easy and quite independent of the location of the casing 10, because such casings 10 are more often than otherwise 25 so located as to preclude the shaft being pulled out axially as has been the practice heretofore.

While only a single form is shown in which this invention may be embodied, it 30 is to be understood that the invention is not limited to any specific construction, but might be applied to various forms without departing from the spirit of the invention or the scope of the appended claims.

35 Having thus described my invention, I claim:

1. A casing structure comprising a fan housing provided with an outlet, said housing having end walls provided respectively 40 with inlets, a shaft passing through said inlets, a fan on said shaft, and means permitting said shaft and fan to be removed as a unit through said outlet.
2. A casing structure comprising a fan 45 housing provided with an outlet, said housing having end walls provided respectively with inlets and slots from the top edge of said walls and opening into said inlets, a shaft arranged to pass through said slots 50 into journalled position in said inlets, top plates removably secured respectively to said housing walls, and means carried by said plates for closing said slots, whereby the removal of said plates opens said slots to 55 permit said shaft and fan to be removed as a unit through said outlet.

3. A casing structure comprising a plurality of fan housings provided respectively with discharge outlets, the end walls of each housing being spaced from the end wall of 60 the adjacent housing, said walls having axially aligned open ended slots, a plurality of fans, one for each housing, a shaft common to said fans and arranged to traverse 65 said slots for removal purposes, removable top plates for closing the respective spaced housing walls, and closures for said slots carried by said top plates, whereby the removal of said plates permits said fans and shafts to be removed as a unit. 70

4. A casing structure comprising a plurality of fan housings provided with removable top plates, a plurality of fans respectively in said housings, a shaft common to said fans, and means attached to said top 75 plates for opening a path for said shaft through said housings, whereby the fans and shaft can be removed as a unit from said housings.

5. A casing structure comprising a casing having an open top portion, a plurality of fan housings spaced apart and having discharge outlets opening into said open top portion, a plurality of fans respectively located in said housings, a shaft common to 80 said fans journalled in said casing, the side walls of said housings having slots opening radially from said shaft, and a plurality of removable top plates normally closing said top portion between the housings, and 85 closures depending from said plates for respectively closing said slots. 90

6. A casing structure comprising a casing having an open top portion, a plurality of fan housings spaced apart and having discharge outlets opening into said open top portion, a plurality of fans respectively located in said housings, a shaft common to 95 said fans journalled in said casing, the side walls of said housings having slots opening radially from said shaft, and a plurality of removable top plates normally closing said top portion between the housings, closures 100 depending from said plates for respectively closing said slots, and interfitting slidable connections between each closure and said housing walls respectively.

Signed at Norristown, county of Montgomery, State of Pennsylvania, this 11th day of February, 1927.

CLARENCE E. SCOTT.
